AMALGAM CARRIERS FOR USE BY DENTISTS
Herbert A. Baughan, 106 E. Main St., Avon Park, Fla.
Filed June 1, 1961, Ser. No. 114,179
6 Claims. (Cl. 32—60)

This invention relates to improvements in amalgam carriers for use by dentists.

An object of the invention is to provide an amalgam carrier which is convenient and comfortable to hold and operate, reliable and efficient in operation, substantially frictionless and rugged and durable in construction.

A further object of the invention is to provide an amalgam carrier whose head or plunger end is extremely slender and compact in design, without the necessity for the bulky "gooseneck" construction found in many present day instruments of this type.

A further object is to provide an amalgam carrier having an improved operating lever and coacting ball bearing means which renders the device extremely smooth in operation.

Still another object is to provide an instrument of the above-mentioned character having an improved spring means associated with the operating lever, and which spring means is stronger and more durable than in prior art devices of this general character.

Other objects and advantages of the invention will be apparent during the course of the following description.

In the accompanying drawings forming a part of this application and in which like numerals are employed to designate like parts throughout the same,

FIGURE 1 is a perspective view of an amalgam carrier according to the invention and illustrating the proper manner for holding the same during use,

FIGURE 2 is an enlarged fragmentary side elevation partly in section of the amalgam carrier,

FIGURE 3 is a further view similar to FIGURE 2 and showing the parts of the device in different operative positions,

FIGURE 4 is a rear side elevation of a tubular member or sleeve which receives the plunger in assembly and showing means to facilitate the introduction of a ball bearing into the sleeve during the assembly of the instrument.

In the drawings, wherein for the purpose of illustration is shown a preferred embodiment of the invention, the numeral 10 designates an elongated preferably cylindrical handle which may have the general proportions of a lead pencil, and including a reduced tapering forward portion 11, as shown. A substantially straight rigid shank 12 is fixedly anchored in any suitable manner within a longitudinal opening 13 in the forward end of the handle, and the shank 12 extends forwardly of the handle 10 for an appreciable distance, as shown, and carries a preferably cylindrical plunger head 14, integral therewith, and arranged at an obtuse angle thereto and projecting below the shank 12 for some distance as shown in the drawings. The plunger head 14 may be provided at its top and slightly above the shank 12 with an inclined flat abutment face 15, serving as a positive stop to limit the downward swinging movement of an operating lever to be described.

Surrounding the plunger head 14 and slidable thereon for axial reciprocation is a carrier sleeve or tube 16 which is substantially cylindrical and has its lower end open as at 17. The top end of the carrier sleeve 16 is closed by a spherically rounded end wall 18, adapted to serve as a retaining pocket for a ball bearing 19.

The carrier sleeve 16 is provided in its rear side with an elongated slot 20, FIGURE 4, extending from a point near and below the extreme top of the sleeve to a point somewhat below its longitudinal center and yet consider-

2

ably above its lowermost end. The lower portion 21 of the slot 20 is preferably enlarged as shown, to facilitate the introduction of the ball bearing 19 into the carrier sleeve during the initial assembly of the instrument as will be further described. If preferred, the carrier sleeve 16 may be slightly flanged as at 22, adjacent the lower end of the slot 20 to add strength to the carrier sleeve and to provide a durable abutment surface for the shank 12 during the operation of the instrument. The flange 22 may be omitted entirely if preferred. The carrier sleeve 16 has a relatively close but free sliding fit upon the plunger head 14, and the latter is adapted to be completely housed within the carrier sleeve in one adjusted position of the latter, FIGURE 2, and the carrier sleeve 16 is considerably longer than the plunger head as shown in the drawings.

An improved operating lever 23 for the carrier sleeve 16 is provided upon the upper side of the handle 10 and near its forward end as well illustrated in FIGURE 2. The lever 23 is pivoted at 24 intermediate its ends upon a pair of short upstanding lugs 25, formed integrally upon the handle 10 and spaced apart laterally to receive the lever 23 therebetween for vertical swinging movement. The lever 23 is slender and is disposed close to and generally parallel with the handle 10 for the sake of maximum compactness. At its rear end, the operating lever 23 carries an integral cup-shaped finger rest 26 for convenient engagement by the index finger, FIGURE 1, while the instrument is held generally in the manner of a pen or pencil during use.

The operating lever 23 has a forwardly extending slender pin extension 27, rigid therewith, and lying close to and substantially parallel with the shank 12 when the plunger head 14 is retracted into the carrier sleeve as in FIGURE 2. The pin extension 27 is substantially straight and is preferably provided at its frontal portion and upon its top and bottom sides with flat faces 28 and 29 for engagement respectively with the ball bearing 19 and the flat abutment face 15. The pin extension 27 extends movably through the upper portion of the slot 20 and through another short slot 30 formed in the forward side of the carrier sleeve 16 near and below its upper end. When the lever 23 is rocked upon its pivot 24, FIGURE 3, the pin extension 27 partakes of a sliding camming action against the ball bearing 19 to retract or lift the carrier sleeve 16 toward the position shown in FIGURE 3. The pin extension 27 at this time shifts or moves longitudinally through the slots 20 and 30, as shown. The carrier sleeve 16 cannot rotate upon the cylindrical plunger head 14 due to the presence of the shank 12 and pin extension 27 within the slots of the sleeve. The ball bearing 19 cannot escape from its socket in the top of the carrier sleeve, after final assembly, due to the arrangement of the elements 27 and 14 within the carrier sleeve.

In order to yieldably hold the operating lever 23 and the carrier sleeve 16 in their positions shown in FIGURE 2, a sturdy torsional coil spring 31, preferably embodying several turns or coils, surrounds the pivot pin 24, within and under the lever 23. This coil spring has end extensions 32 and 33 which bear respectively against the under side of the lever 23 and the upper side of the handle 10, as shown. The handle may be recessed slightly as at 34 to seat the spring extension 33. The spring extension 32 will be seated between the side flanges of the operating lever 23 which is concave in cross section.

During use, the dentist grasps the instrument in the manner shown and described and with the operating lever 23 positioned as in FIGURE 2 under influence of spring 31, the dentist loads the bottom open end of the carrier sleeve 16 with soft amalgam by jabbing the sleeve into

the amalgam mass several times until the sleeve is filled. The spring 31 is heavy enough to resist upward pressure upon the sleeve 16 during the normal loading operation.

After loading the instrument, the dentist carries the same adjacent to the tooth cavity and expels the amalgam from the carrier sleeve 16 by placing pressure with the index finger upon the cup-shaped rest 26 of the operating lever 23. When this is done, the lever 23 turns clockwise upon its pivot 24 and the carrier sleeve is elevated or retracted relative to the plunger head 14, FIGURE 3, and the plunger head expels the amalgam from the carrier sleeve. Upon release of the operating lever 23, the spring 31 quickly returns the parts to their relative positions shown in FIGURE 2, and the instrument is ready for reloading and continued use.

Provision of the ball bearing 19 at the top of the carrier sleeve renders the device substantially frictionless and very smooth in operation and also very sturdy in construction. The design of the working head end of the instrument is highly compact and slender to facilitate working in cramped areas of the mouth.

In this connection, if preferred, the plunger head 14 and carrier sleeve 16 may be set at an acute angle to the shank 12 and handle 10, rather than at an obtuse angle thereto as shown. That is to say, the axis of the handle may form an acute angle with the axis of the carrier sleeve and may also form an acute angle with and below a horizontal line with which the axis of the carrier sleeve forms a right angle. All other parts and their operation would remain identical in the case where the carrier sleeve and plunger head form an obtuse angle with the handle of the instrument.

It is to be understood that the form of the invention herewith shown and described is to be taken as a preferred example of the same, and that various changes in the shape, size and arrangement of parts may be resorted to, without departing from the spirit of the invention or scope of the subjoined claims.

Having thus described my invention, I claim:

1. An amalgam carrier and applicator comprising a handle, a plunger head secured to the forward end of the handle and extending generally transversely thereof and beyond one side of the same, a carrier sleeve slidably mounted upon the plunger head for reciprocation axially thereof, said carrier sleeve having one open end and portions defining a longitudinal slot through its side wall to receive a part of said handle, other portions of said carrier sleeve defining an opening through the side wall of the carrier sleeve diametrically opposite said longitudinal slot, a concave top end wall for the carrier sleeve closing the other end thereof and forming a spherical seat, a ball bearing element disposed within said seat, an operating lever pivoted upon said handle for swinging movement relative thereto and having a slender pin extension engaging movably through said slot and opening of the carrier sleeve and disposed between the ball bearing element and said plunger head to cammingly engage the ball bearing element, and resilient means interconnecting said operating lever and handle to bias the handle in a direction to cause the open end of the carrier sleeve to be normally positioned forwardly of the leading end of said plunger head.

2. An amalgam carrier and applicator comprising a handle having a reduced shank portion, a plunger head secured to said reduced shank portion at the forward

end thereof and extending generally transversely of the shank portion, a carrier sleeve having one open end surrounding said plunger head and slidably thereon for axial reciprocation relative thereto, said carrier sleeve having portions defining a longitudinal slot through its side wall to receive said shank portion and other portions, a side wall opening diametrically opposite to said slot, means defining a ball bearing seat on the upper end of said carrier sleeve opposite said open end and above said plunger head, a ball bearing disposed within said seat, an operating lever rockably mounted upon said handle and having a forward extension projecting between said ball bearing and plunger head to cammingly contact the ball bearing and extending through said slot and opening in said carrier sleeve, and a spring associated with the operating lever to bias the latter in a direction to maintain the open end of the carrier sleeve forwardly of the free end of said plunger head.

3. An amalgam carrier and applicator according to claim 2, and wherein said forward extension of the operating lever includes flat top and bottom faces, said plunger head having an inclined flat top end face engageable with the flat bottom face of said extension, the flat top face of said extension contacting said ball bearing rollingly.

4. An amalgam carrier and applicator according to claim 2, and wherein said spring is a torsional coil spring engaging said handle and operating lever, and a pivot element interconnecting the operating lever and handle pivotally and carrying said spring.

5. An amalgam carrier and applicator according to claim 2, and wherein said longitudinal slot in said carrier sleeve is enlarged at its lower end to facilitate the introduction of said ball bearing through said slot and into said sleeve prior to the assembling of the operating lever with said handle.

6. An amalgam carrier and applicator comprising a handle having a reduced forward shank, a cylindrical plunger head carried by the forward end of said shank at an angle thereto generally transversely thereof, a carrier sleeve slidably mounted upon the plunger head and having an open end and an opposite closed end forming a ball bearing seat, a ball bearing disposed within said seat freely, the carrier sleeve having portions thereof defining an elongated slot in its side wall intermediate its ends and other portions defining a short slot in its side wall near its closed end and diametrically opposite the elongated slot, a pivot element carried by said handle close to one side thereof, a longitudinal lever pivoted upon said pivot element and rockable thereon with respect to the handle, a torsion coil spring surrounding the pivot element and having end extensions bearing on the handle and said lever and biasing the lever in one direction, and a slender pin extension on the forward end of the lever engageable through said slots and movable therein and interposed between the ball bearing and one end of said plunger head.
